US0D1056918S

(12) **United States Design Patent** (10) **Patent No.:** **US D1,056,918 S**
(45) **Date of Patent:** **** Jan. 7, 2025**

(54) **CARTRIDGE FOR GAME APPARATUS**

(71) Applicant: **NINTENDO CO., LTD.**, Kyoto (JP)

(72) Inventors: **Shinji Hirose**, Kyoto (JP); **Yuta Fujita**, Kyoto (JP)

(73) Assignee: **Nintendo Co., Ltd.**, Kyoto (JP)

(**) Term: **15 Years**

(21) Appl. No.: **29/961,158**

(22) Filed: **Sep. 4, 2024**

Related U.S. Application Data

(63) Continuation of application No. 29/944,332, filed on May 28, 2024, now Pat. No. Des. 1,051,131, which is a continuation of application No. 29/935,355, filed on Apr. 1, 2024, now Pat. No. Des. 1,035,775, which is a continuation of application No. 18/443,746, filed on Feb. 16, 2024, which is a continuation of application No. 17/497,227, filed on Oct. 8, 2021, now Pat. No. 12,027,789, which is a continuation of application No. 15/799,082, filed on Oct. 31, 2017, now Pat. No. 11,171,433, which is a continuation of application No. 15/398,903, filed on Jan. 5, 2017, now Pat. No. 9,853,379.

CLAIM

The ornamental design for a cartridge for game apparatus, as shown and described.

DESCRIPTION

FIG. 1 is a rear view of a cartridge for game apparatus according to our new design; and,

FIG. 2 is rear perspective view thereof.

The broken lines in the drawings depict portions of the cartridge for game apparatus that form no part of the claimed design.
